UNITED STATES PATENT OFFICE.

PHILIP LANE SCOTT, OF CHICAGO, ILLINOIS, ASSIGNOR TO SUPER-DIESEL TRACTOR CORPORATION, OF LA PORTE, INDIANA, A CORPORATION OF NEW YORK.

FUEL PUMP AND OIL-INJECTION SYSTEM FOR INTERNAL-COMBUSTION ENGINES.

Application filed December 1, 1920. Serial No. 427,642.

My invention has to do with the pump and the pipe and connections whereby I am enabled to inject oil or fuel into an internal combustion engine by pressure applied to the fuel 5 itself alone and without the use of any air pump or jet or any other additional apparatus.

One object of my invention is to provide an arrangement whereby any entrainment of 10 foreign materials such as air, gas and the like may be prevented. Another object of my invention is to provide means whereby the system may be automatically and continually cleared of any air, gas or other foreign substances and thus any air dome action may be 15 prevented. Other objects of my invention will appear from time to time.

In dealing with my invention it must be remembered that I am planning on what I prefer to call solid injection of a liquid under 20 the influence of hydraulic pressure only for the purpose of breaking up or atomizing the liquid. The more incompressible and solid the liquid is, the better will be the action and 25 the presence of gas in appreciable quantities is sufficient to make my spray and atomizing action become either in-operative or exceedingly unsatisfactory. This is true of 30 all pump systems in general of this kind and that means that the inclusion of even a slight amount of gas or air may become exceedingly disadvantageous. This difficulty arising from too great compressibility of liquid is important even where injection with air is used, 35 as for instance it might result in too great a proportion of the pump stroke being used up before actual discharge took place, or it might result in such a changing of the timing that the injection would not take place in 40 time to fit in with the engine cycle and these difficulties are greatly accentuated when solid injection into the engine itself is relied upon as in the case in my apparatus.

This difficulty arising out of the presence 45 of gases in the liquid may take a number of forms. This difficulty arises from the fact that all of the oil with which we deal always contains a certain amount of air or other gas in solution in such minute quantities that it 50 is practically if not actually impossible to get rid of them mechanically. These gases may be in such small bubbles that they cannot be seen and the only way to avoid difficulty arising from this situation is to arrange to handle under pressure the smallest possible solu-

tion of liquid and to arrange to inject under pressure as large a proportion of the volume subjected to pressure as possible.

Another form of the gas difficulty arises from the fact that when the temperature rises, 60 for instance when the oil goes into the warm oil pump or when the pressure drops as on successive strokes, this gas or air may be found to form appreciable bubbles and these bubbles may or may not join themselves to bubbles of air introduced by leakage in the suction system or improper handling during the operation. This may and frequently does result in the presence in the system of relatively large air or gas bubbles and there are 65 four forces gravity, entraining, drop in pressure, and warming, which may be used in getting rid of these bubbles. The first is that heating the liquid and reducing its pressure both tend to separate out and to liberate from 70 the liquid the gas or air which may be therein contained; the second is that gravity acting perhaps more slowly will segregate the separated gas or air bubbles and the fourth force available is the entraining power of a rapidly 75 moving stream or column of oil which can be used to pick up and carry away the segregated bubbles of air or gas.

In order then to take advantage of the two forces which can be used to keep the system 80 clear of bubbles it is desirable first to place the mechanism which is to be used in removing the air at the high point in the system so as to gain the benefit of gravity, and it is necessary to provide means for the movement of as large a body of oil as is possible 85 toward this point. In order that gas or air bubbles may not be entrapped or left at any point short of the place where they are to be separated out, it is desirable first to provide a system where there shall be no re-entering places or corners, no pockets where the air may stagnate, no places where the air 90 may be caught and held by gravity and it is necessary to provide a system where the oil has relatively high velocity at all times. In addition to this, it is necessary that the passage or aperture through which that part of the oil which is going to be actually burned in the engine or discharged into the engine 95 be placed as far from the point where the air laden oil should be discharged as is convenient because in my apparatus it is necessary that whatever part of the oil is discharged 100 conveying away with it, this unwelcome air,

none of it shall find its way to the spray valve because if it tried so to do this would result in immediate air binding or other unsatisfactory operation at the spray nozzle. It also seems best that the air laden oil be discharged at another time as well as at another place from the fuel entering the engine.

My invention is illustrated more or less diagrammatically in the accompanying drawings wherein:

Figure 1 is a section through the pump cylinder and associated parts on a plane containing the pump plunger;

Figure 2 is a section along the line 2—2 of Fig. 1;

Figure 3 is a section along the same plane as Fig. 1 showing the pump or plunger driving mechanism;

Figure 4 is a section along the line 4—4 of Fig. 3.

A is a pump casing. It includes a pump cylinder A' in which is mounted for reciprocation a pump plunger A² having a tapered nose A³. This pump casing contains within its walls a plurality of pockets or sockets to contain the various valves and connections which will later be disclosed. A⁴ is a socket in line with the pump chamber itself adapted to contain a bypass or valve housing. A⁵ is a socket at right angles to the valve cylinder adapted to contain an inlet valve housing, and A⁶ is a socket at right angles to the pump cylinder and the socket A⁵ adapted to contain a discharge valve housing. The valve cylinder communicates directly with the socket A⁴ and with the sockets A⁵ and A⁶, almost directly through the exceedingly short passages A⁷ and A⁸, whose arrangement is such that the housings contained by these sockets are as close to the pump plunger as possible.

Extending rearwardly from the end of the pump housing A is a housing B¹⁵ having a pair of brackets B, B'. These brackets form a frame-work in which the cam shaft B² is mounted for rotation. This cam shaft is driven from the engine or from some other power source, if the atomizer is used in connection with devices other than engines, and by any suitable power transmission connection not here shown. B³ is a cam rigidly mounted on the cam shaft. The face of this cam is in contact with the roller B⁴ which roller is in turn mounted upon a pin B⁵ and this pin is connected to a cross head or carrier B⁶, which cross head is slidably mounted in the cylindrical bore B¹⁶ in the housing B¹⁵. The cross head having the extended lugs B¹⁷ and slotted at B¹⁸ to allow guidance on the shaft B². B⁷ is a ball substantially spherically mounted on the crank end of the plunger A². B⁸ is a yoke or spring guide having a spherical bearing B⁹ to engage the under side of the ball B⁷. B¹⁰ is a coiled spring surrounding the cap B⁸ and

adapted to be compressed between the collar B¹¹ and the pump housing. B¹³ is a pin projecting forward from the cross head B⁶ and engaging the outer side of the ball B⁷. It will be noted that there is clearance between the cross head B⁶ and the yoke or spring guide B⁸ and that this yoke or guide is in bearing engagement as at B¹⁴, with an enlargement on the pin B¹³ so that the compression of the spring keeps the ball always firmly clamped between the yoke B⁸ and the pin B¹³, the arrangement being such that as the cam rotates the piston is forced forward, a rigid drive being applied through the pin B¹³ to pump in a forward direction as the cam. As the cam goes through the piston or plunger is drawn back by the spring B¹⁰.

C is the intake valve housing. It is seated in the socket A⁵ by means of a yoke C', and anchor bolts C². This housing is provided at its inner extremity with a beveled valve seat C³ upon which is seated a conical intake valve C⁴, this valve being held upon the seat by the coiled spring C⁵, and guided as it reciprocates by the vanes C⁷. The inner face of the valve block, that is that part which is removed from the beveled seat is conical in shape as shown at C⁸, there being a series of small lugs C⁹ projecting from the conical face. The face of the socket A⁵ is also conical to conform to the conical face of the valve the arrangement being such that when the plunger A² is drawn back the suction will unseat the valve but the valve will be held away from the conical bottom of the socket so that there is a free passage for oil in through the intake valve housing across the beveled seat, around the conical end of the valve into the plunger chamber or valve cylinder. C¹⁰ is a pipe leading from any suitable source of oil supply whereby oil may be drawn up into the pump cylinder through the valve housing.

It will be noted that the point at which the intake part of the system communicates, the valve cylinder is at the bottom of the cylinder so that any entrained air or gas bubbles will pass right through the intake system up into the pump cylinder and there will be no tendency for any air or gas bubbles to be pocketed anywhere within this part of the system.

D is a discharge valve housing seated in the socket A⁶ by means of a yoke D' and holding bolts D². This discharge valve housing terminates at the inner end immediately adjacent the pump plunger in a narrow conical valve seat D³, the opening through this valve seat being closed by a pointed conical or needle valve D⁴ slideable in the housing and guided therein by a series of vanes D⁵. D⁶ is a rigid spring seating this discharge valve, and D⁷ is an oil pipe or conduit leading from the discharge valve housing to a spray nozzle or member not here shown.

It will be noted that the passage leading

from the pump cylinder to the discharge valve is above the discharge of the intake valve, but still is below the highest part of the system, in this case the upper portion of the pump cylinder, so that any bubbles of gas or air which may rise up through the system will still be caught in the pump cylinder above the point at which the oil is discharged.

E is the by-pass valve housing which is contained within the socket A⁴ as is the socket itself in line with the pump cylinder. The inner end of this housing is provided with an extension E' which penetrates into the pump cylinder. This extension is hollowed out in conical form as at E² to conform to the shape of the conical or pointed nose of the pump plunger. The discharge from the pump cylinder through this housing takes place at the apex of the cone where a very narrow passage E³ is adapted to be closed by a needle valve E⁴. This needle valve is carried by a reciprocable pin E⁵ projecting out through the stuffing box E⁶. E⁷ is an oil discharge passage communicating with the interior of the by-pass valve housing so that any oil that passes out into that housing may escape and be caught in any suitable way not here illustrated. E⁸ is a controlled rod. It may lead to an engine governor or to a manually controlled member, or it may be operated or moved by any other suitable means. It is slideable in bearings E⁹ E¹⁰ and has a lever E¹⁰ extending over to engage the pin E⁵. It engages a collar E¹¹ on that pin, and when the member E⁸ is moved to the right as in Fig. 1 the spring E¹² will be compressed and the valve unseated, since the parts move in the opposite direction, and therefore will be immediately closed. The sole function of the spring E¹² is to keep the collar E¹¹ always firmly seated on the lever E¹⁰ unless and until the lever moves back too far and the movement of the collar is arrested by the seating of the needle valve. The purpose and operation of this spring is exactly the same as the purpose and operation of the valve springs in ordinary automobile engines, that is it keeps the parts tight, seats the valve, makes it unnecessary to have as close fits and accurate workmanship as otherwise would be necessary.

The pump cylinder is counterbored out around the piston immediately in line with the two right angle valve sockets. The bearing of the cylinder is fitted closely by the plunger. The need for this arrangement, is that experience shows that in the very tight fits that are used, it sometimes happened that if one of the valve housings is removed, and afterwards replaced, it may be drawn up so tight that the piston will actually bind. In order therefore, to provide clearance and still make it possible to have the pump tight this slight counterboring is adopted.

I have shown in my drawings an operative

device, still many changes may be made in size, shape and arrangements of parts without departing from the spirit of my invention.

The pump is designed, as has been explained above, primarily to be used in connection with internal combustion engines. As designed it is expected to be associated very closely with that engine and is not itself artificially cooled. It will therefore in operation be heated by the heat generated by the engine, and since it is not cooled, it will remain heated.

A feature of great importance in the invention is the use of a single high point in the pump chamber to which the incoming liquid is drawn. The pump chamber with its associated passages is so shaped that in its normal flow the liquid upon entering the chamber will tend to pass to a high point in the system and will be momentarily brought comparatively to a stand still at that point. Thus the entrained air and gas is carried by the flow of the liquid to this high point and because of this movement, gravity assists in the separation of the air and gas, and because at this point the flow of liquid is momentarily stopped, gravity is enabled more completely to act further to assist in the separation. This high point is above the point of discharge to the engine cylinder so that when fuel is discharged into the engine cylinder, there is no tendency to entrain the air and gas in the fuel charge which is being discharged into the engine cylinder. The shape of the pump chamber is such, however, that in the by-passing operation the air and gas will be readily and positively entrained, and by means of the regular flow and the high speed of the flowing liquid, will be carried from the high point, off through the by-pass valve. The shape of the parts is thus arranged to co-operate in segregating and isolating the air and gas, and in holding such segregated air and gas from the fuel charge which is injected into the engine and in conducting it to the by-pass opening at the time of by-passing.

The use and operation of my invention are as follows:

The pump plunger reciprocates in time with the engine, if it is engine driven, or in time with the driving mechanism if an engine is not involved. As it reciprocates moving in a back direction, it in the usual manner sucks up into the system this oil, which passes in a relatively high velocity through the intake valve sweeping over all parts of the intake system, and since there are no dead spots or inwardly reentrant pockets, there is no possibility of stagnation in that system and no chance that the segregation of air or gas laden oil, or the formation and caging of any bubbles. Any bubbles or any gas or air laden oil will thus pass up into the pump cylinder, and since at the end of the stroke there is little if any turbulence such gas or air laden

oil will have opportunity to rise to the top of the pump cylinder. Upon the return stroke of the pump plunger pressure will immediately be generated and almost immediately that pressure will be great enough to unseat the discharge valve, and the oil from beneath that part of the pump cylinder where segregation of the lighter air or gas laden part of the oil takes place, will be discharged through the discharge valve to the spray nozzle or spray member or engine cylinder as the case may be.

As the pumping movement of the plunger continues the pointed end of the plunger will penetrate within the conical portion of the by-pass valve housing. At some point during this the governor or the hand of the operator or any other suitable timing or turning source will open the by-pass valve. When that happens pressure will instantly drop and the discharge valve instantly close and as the pump plunger continues to reciprocate oil will be forced out ahead of the pointed piston through the by-pass valve. This arrangement of a pointed piston or plunger and pointed socket toward which it moves is provided in order to permit relatively high liquid velocities even before the end of the stroke and that together with the wiping action of the shoulder of the plunger within the pump cylinder will tend to force or drive or entrain all the lighter segregated bubbles or air or gas laden oil out through the by-pass valve. The result of this is that by each reciprocation of the plunger the system is cleared of all the segregated gas or air and there is thus no time for any appreciable quantity to be caught within the system.

In pointing out and claiming the processes which form part of my invention, I have been compelled to name the several steps in order but it will be understood the order in which I have named them is not of the essence of the invention and in many instances the order can and perhaps should be changed. In addition with the gravity separating the air or gas bubbles after they have been formed are entrained by the flowing current of the liquid in the system at a relatively high rate of speed and by this entrainment they are carried toward the place at which it is desired that they shall be left and segregated out as they reach that point. The arrangement of the parts is such that the facilities will decrease so that these air bubbles will be deposited at the desired position and left there. This action takes place independent of the operation of gravity and has or may be in a sense largely supplementary to the gravity action.

I have shown in the drawings, particularly in Figures 1 and 2 clearances in the assembly of the parts. Thus the member E¹ is shown with a clearance about its outside. This is not a clearance which is open for liquid, it is

simply such a clearance as permits the parts in assembly to be fitted together.

It will be noted that in the design of the applicant every effort has been made to reduce the clearances between the plunger, barrel and other adjacent parts to the minimum possible. The reason for this is that the air and gas laden oil which is to be discharged must move at high velocity during the time of discharge in order that all bubbles which have considerable tendency to adhere to the walls of the chamber may be surely and positively swept out of the pump chamber.

I claim:

1. A liquid atomizing system comprising a pump chamber, a liquid supply conduit, a suction valve therein, a spray nozzle, a conduit between it and the pump chamber, a discharge valve therein, a by-pass discharge passage leading from the pump chamber and a mechanically operated release valve controlling it, the conduit leading to the spray nozzle discharging from the pump chamber at a point appreciably below the highest point thereof, a piston adapted to reciprocate in the pump chamber, having a pointed end, the pump chamber terminating in a conical portion substantially the same size and shape as the pointed end of the plunger, the by-pass discharge passage leading from the apex of such conical portion.

2. A liquid atomizing system comprising a pump chamber, a liquid supply conduit, a suction valve therein, a spray nozzle, a conduit between it and the pump chamber, a discharge valve therein, a by-pass discharge passage leading from the pump chamber and a mechanically operated release valve controlling it, the by-pass discharge passage leading from the pump chamber along the axis thereof, the conduit leading to the spray nozzle discharging from the pump chamber at a point appreciably below the highest point thereof, a piston adapted to reciprocate in the pump chamber, having a pointed end, the pump chamber terminating in a conical portion substantially the same size and shape as the pointed end of the plunger, the by-pass discharge passage leading from the apex of such conical portion.

3. A pump comprising a cylindrical pumping chamber, a plunger of substantially the same cross section thereas and having a conical nose, the chamber terminating in a conical pocket into which the nose of the plunger is adapted to fit, intake and discharge ports in the cylindrical part of the chamber and a second discharge port at the apex of said pocket.

4. A pump comprising a cylindrical pumping chamber, a plunger of substantially the same cross section thereas and having a conical nose, the chamber terminating in a conical pocket into which the nose of the plunger is

adapted to fit, intake and discharge ports in the cylindrical part of the chamber, and a second discharge port at the apex of said pocket, there being only sufficient clearance between the wall of the chamber and the plunger about the intake and discharge ports to prevent binding of the plunger.

5. A pump comprising a cylindrical pumping chamber, a plunger of substantially the same cross section thereas and having a conical nose, the chamber terminating in a conical pocket into which the nose of the plunger is adapted to fit, intake and discharge ports in the cylindrical part of the chamber and a second discharge port at the apex of said pocket, the end of the chamber being closed by a separate plug, which is cut away to form the pocket into which the plunger penetrates.

6. In a liquid pressure system a combined settling tank and pump cylinder located in the high point thereof, intake and discharge ports in the walls thereof below the high point, a pump plunger mounted for reciprocation in the cylinder and an air and liquid discharge port arranged in one end of the cylinder axially in line with the pump plunger, the piston being of substantially the same diameter as the cylinder and being adapted to substantially fill the cylinder at the inner end of its stroke.

7. In a liquid pressure system a combined settling tank and pump cylinder located in the high point thereof, intake and discharge ports in the walls thereof below the high point, a pump plunger mounted for reciprocation in the cylinder and an air and liquid discharge port arranged in one end of the cylinder axially in line with the pump plunger, the pump plunger having a conical nose, the axial discharge port being at the apex of a conical pocket in which said nose is adapted to fit.

8. In a liquid pressure system a combined settling tank and pump cylinder located in the high point thereof, intake and discharge ports in the walls thereof below the high point, a pump plunger mounted for reciprocation in the cylinder and an air and liquid discharge port arranged in one end of the cylinder axially in line with the pump plunger, the piston being of substantially the same diameter as the cylinder and being adapted to substantially fill the cylinder at the inner end of its stroke, the pump plunger having a conical nose, the axial discharge port being at the apex of a conical pocket in which said nose is adapted to fit.

9. In a liquid atomizing system, comprising a pump, a discharge port and a series of conduits, means for segregating the gas and air included in the liquid at a high point in the system, means for discharging a part of the liquid through the spray nozzle and independent means for separately expelling the segregated gas and air from the system

the pump comprising a plunger having a pointed nose, a pocket in the end of the pump chamber into which said nose is adapted to penetrate, the discharge for the segregated material being from the apex of such pocket.

10. In a liquid atomizing system comprising a pump, a discharge port and a series of conduits, means for segregating the gas and air included in the liquid at a high point in the system, means for discharging a part of the liquid through the spray nozzle and independent means for separately expelling the segregated gas and air from the system, a pressure actuated valve controlling the spray nozzle and a mechanically controlled valve controlling such separate discharge of the segregated material, the pump comprising a plunger having a pointed nose, a pocket in the end of the pump chamber into which said nose is adapted to penetrate, the discharge for the segregated material being from the apex of such pocket.

11. In a liquid atomizing system comprising a pump, a discharge port and a series of conduits, means for segregating the gas and air included in the liquid at a high point in the system, means for discharging a part of the liquid through the spray nozzle and independent means for separately expelling the segregated gas and air from the system, a pressure actuated valve controlling the spray nozzle and a mechanically controlled valve controlling such separate discharge of the segregated material, the pressure actuated valve being set to close immediately upon opening of the mechanically controlled valve, the pump comprising a plunger having a pointed nose, a pocket in the end of the pump chamber into which said nose is adapted to penetrate, the discharge for the segregated material being from the apex of such pocket.

12. In a liquid atomizing system, comprising a pump, a discharge port and a series of conduits, means for segregating the gas and air included in the liquid at a high point in the system, means for discharging a part of the liquid through the spray nozzle and independent means for separately expelling the segregated gas and air from the system, the communication between the pump and the spray nozzle being located in the wall of the pump chamber, below the high point thereof, the discharge for the segregated air and oil being located in the end of the cylinder on the axis thereof, the pump comprising a plunger having a pointed nose, a pocket in the end of the pump chamber into which said nose is adapted to penetrate, the discharge for the segregated material being from the apex of such pocket.

13. In a liquid atomizing system comprising a pump, a discharge port and a series of conduits, means for segregating the gas and air included in the liquid at a high point in the system, means for discharging a part of

the liquid through the spray nozzle and independent means for separately expelling the segregated gas and air from the system, a pressure actuated valve controlling the spray nozzle and a mechanically controlled valve controlling such separate discharge of the segregated material, the communication between the pump and the spray nozzle being located in the wall of the pump chamber below the high point thereof, the discharge for the segregated air and oil being located in the end of the cylinder on the axis thereof, the pump comprising a plunger having a pointed nose, a pocket in the end of the pump chamber, into which said nose is adapted to penetrate, the discharge for the segregated material being from the apex of such pocket.

14. In a liquid atomizing system comprising a pump, a discharge port and a series of conduits, means for segregating the gas and air included in the liquid at a high point in the system, means for discharging a part of the liquid through the spray nozzle and

independent means for separately expelling the segregated gas and air from the system, 25 a pressure actuated valve controlling the spray nozzle and a mechanically controlled valve controlling such separate discharge of the segregated material, the pressure rotated valve being set to close immediately upon 30 opening of the mechanically controlled valve, the communication between the pump and the spray nozzle being located in the wall of the pump chamber, below the high point thereof, the discharge for the segregated air and oil 35 being located in the end of the cylinder on the axis thereof, the pump comprising a plunger having a pointed nose, a pocket in the end of the pump chamber, into which said nose is adapted to penetrate, the discharge 40 for the segregated material being from the apex of such pocket.

Signed at Chicago, county of Cook and State of Illinois, this 29 day of November 1920.

PHILIP LANE SCOTT.
